CLAIM

The ornamental design for a jig for attaching display protection film, as shown and described.

DESCRIPTION

FIG. 1 is a perspective view of a jig for attaching display protection film;

FIG. 2 is a front view of the jig for attaching display protection film as shown in FIG. 1;

FIG. 3 is a rear view of the jig for attaching display protection film as shown in FIG. 1;

FIG. 4 is a left side view of the jig for attaching display protection film as shown in FIG. 1;

FIG. 5 is a right side view of the jig for attaching display protection film as shown in FIG. 1;

FIG. 6 is a top plan view of the jig for attaching display protection film as shown in FIG. 1; and,

FIG. 7 is a bottom view of the jig for attaching display protection film as shown in FIG. 1.

Any components in the drawings shown in broken lines are for illustrative purposes only and form no part of the claimed design.

1 Claim, 7 Drawing Sheets
